ABSTRACT

A system for powering electric hydraulic fracturing equipment, the system including a power storage system and electric powered hydraulic fracturing equipment in selective electrical communication with the power storage system. The system further includes at least one circuit breaker between the power storage system and the electric powered hydraulic fracturing equipment, the circuit breaker configured to facilitate or prevent electrical communication between the power storage system and the electric powered hydraulic fracturing equipment.

HIGH CAPACITY POWER STORAGE SYSTEM FOR ELECTRIC HYDRAULIC FRACTURING

CROSS REFERENCE TO RELATED APPLICATIONS

This application claims priority to and the benefit of, U.S. Provisional Application Ser. No. 62/881,714, filed Aug. 1, 2019, the full disclosure of which is hereby incorporated herein by reference in its entirety for all purposes.

BACKGROUND

1. Field of Invention

This invention relates in general to equipment used hydraulic fracturing operations, and in particular, to electricity storage at a hydraulic fracturing site.

2. Description of the Prior Art

Hydraulic Fracturing is a technique used to stimulate production from some hydrocarbon producing wells. The technique involves injecting hydraulic fracturing fluid into a wellbore at a pressure sufficient to generate fissures in the formation surrounding the wellbore. Hydrocarbons can then flow through the fissures to a production bore. The hydraulic fracturing fluid is typically injected into the wellbore using hydraulic fracturing pumps, which can be powered, in some cases, by electric motors. The electric motors can in turn be powered by generators.

Preserving and extending the life and durability of power generators at an electric hydraulic fracturing site is a priority. This objective, however, can be undermined by overloading power generation equipment. Such overloading reduces the life span of the equipment, and can also create a hazardous environment at a wellsite due to malfunctions and overheating in close proximity with other hydraulic fracturing equipment.

The fast response electricity storage system of the present technology is one viable option to assisting in power distribution, in particular at times when power generation equipment is overloaded. Not only does such a system provide a rapid and effective way to supply power when demand is high, but it also possesses other features that help provide continuous reliable power to hydraulic fracturing equipment.

SUMMARY

One embodiment of the present technology provides a hydraulic fracturing power system, including a power source, a power storage system, and electric powered hydraulic fracturing equipment in selective electrical communication with the power source, the power storage system, or both. The system further includes at least one circuit breaker between the power source, the power storage system, or both, and the electric powered hydraulic fracturing equipment, the circuit breaker having an open position that opens an electric circuit between the electric powered hydraulic fracturing equipment and the power source, the power storage system, or both, and a closed position that closes the electric circuit.

In some embodiments, the power storage system can be at least one solid state battery selected from the group consisting of electrochemical capacitors, lithium ion batteries,

nickel-cadmium batteries, and sodium sulfur batteries. Alternatively, the power storage system can be at least one flow battery selected from the group consisting of redox batteries, iron-chromium batteries, vanadium redox batteries, and zinc-bromine batteries. The at least one battery can be rechargeable.

In certain embodiments, the at least one circuit breaker can include a first circuit breaker and a second circuit breaker, the first circuit breaker electrically connected to the power source, and the second circuit breaker electrically connected to the power storage system. Each of the first circuit breaker and the second circuit breaker can be electrically connected to the electric powered hydraulic fracturing equipment via a common bus. Alternatively, the at least one circuit breaker can be a first circuit breaker, and both the power source and the power storage system can be electrically connected to the first circuit breaker.

In some embodiments, at least one of the power source and the power storage system can be electrically connected to the at least one circuit breaker via a power line. In addition, the power storage system can be mounted on a trailer. Furthermore, the at least one circuit breaker can be substantially enclosed in a switchgear housing.

Another embodiment of the present technology provides a system for powering electric hydraulic fracturing equipment, the system including a power storage system, electric powered hydraulic fracturing equipment in selective electrical communication with the power storage system, and at least one circuit breaker between the power storage system and the electric powered hydraulic fracturing equipment, the circuit breaker configured to facilitate or prevent electrical communication between the power storage system and the electric powered hydraulic fracturing equipment.

In certain embodiments, the power storage system can be at least one solid state battery selected from the group consisting of electrochemical capacitors, lithium ion batteries, nickel-cadmium batteries, and sodium sulfur batteries. Alternatively, the power storage system can be at least one flow battery selected from the group consisting of redox batteries, iron-chromium batteries, vanadium redox batteries, and zinc-bromine batteries.

In addition, certain embodiments of the technology can also include a power source. In such embodiments, the at least one circuit breaker can include a first circuit breaker and a second circuit breaker, the first circuit breaker electrically connected to the power source, and the second circuit breaker electrically connected to the power storage system. Alternatively, the at least one circuit breaker can be a first circuit breaker, and wherein both the power source and the power storage system are electrically connected to the first circuit breaker.

Some embodiments can include a power source, wherein at least one of the power source and the power storage system are electrically connected to the at least one circuit breaker via a power line, and wherein the at least one circuit breaker is substantially enclosed in a switchgear housing. Furthermore, the power source can be rechargeable. Alternatively, the power source can be electrically connected to the at least one circuit breaker via a power line, and the power storage system can be located adjacent the switchgear housing and electrically coupled directly to the switchgear without a power line.

Additionally, yet another embodiment can include software in communication with the power storage system, the software configured to monitor the state of the power storage system and to integrate control of the power storage system

with other features of the system for powering electric hydraulic fracturing equipment.

BRIEF DESCRIPTION OF THE DRAWINGS

The present technology will be better understood on reading the following detailed description of non-limiting embodiments thereof, and on examining the accompanying drawings, in which:

FIG. 1A is a schematic diagram of a hydraulic fracturing power system according to an embodiment of the present technology;

FIG. 1B is a schematic diagram of a power storage system as used in the embodiment of the hydraulic fracturing power system of FIG. 1A;

FIG. 2A is a schematic diagram of a hydraulic fracturing power system according to an alternate embodiment of the present technology;

FIG. 2B is a schematic diagram of a power storage system as used in the embodiment of the hydraulic fracturing power system of FIG. 2A;

FIG. 3A is a schematic diagram of a hydraulic fracturing power system according to another alternate embodiment of the present technology;

FIG. 3B is a schematic diagram of an alternate embodiment of the hydraulic fracturing power system of FIG. 3A;

FIG. 4A is a schematic diagram of a hydraulic fracturing power system according to yet another alternate embodiment of the present technology; and

FIG. 4B is a schematic diagram of an alternate embodiment of the hydraulic fracturing power system of FIG. 4A.

DETAILED DESCRIPTION OF THE INVENTION

The foregoing aspects, features and advantages of the present technology will be further appreciated when considered with reference to the following description of preferred embodiments and accompanying drawings, wherein like reference numerals represent like elements. In describing the preferred embodiments of the technology illustrated in the appended drawings, specific terminology will be used for the sake of clarity. The invention, however, is not intended to be limited to the specific terms used, and it is to be understood that each specific term includes equivalents that operate in a similar manner to accomplish a similar purpose.

According to one embodiment of the technology, a fast response electricity storage, or power storage system (PSS) can be provided to supply power to the power generation equipment of an electric hydraulic fracturing fleet when demand is high or in the event of a generator failure. The PSS system can include either solid state batteries or flow batteries. Solid state batteries can include, for example, electrochemical capacitors, lithium ion batteries, nickel-cadmium batteries, and sodium sulfur batteries. In addition, solid state batteries can charge or discharge based on electricity usage, and such charging and discharging can be paired with a software system, to monitor the state of the batteries and control the charging and discharging of the batteries. Flow batteries can, for example, include redox, iron-chromium, vanadium redox, and zinc-bromine batteries, and can be rechargeable batteries that store electricity directly in an electrolyte solution and respond quickly as needed. The flow batteries can also be paired with software, and the software associated with the both solid state and flow batteries can be designed to integrate with an operator's

existing system so that monitoring and control can be integrated with other functions.

FIG. 1A shows a hydraulic fracturing power system 100 according to an embodiment of the present technology. The 5 hydraulic fracturing power system 100 includes a power source 110, which can be, for example, a generator, and which can feed a first circuit breaker 120. As shown, the hydraulic fracturing power system 100 can further include a PSS 130 that can feed a second circuit breaker 140. In some 10 embodiments, both the first circuit breaker 120 and the second circuit breaker 140 can be housed in the same switchgear housing 150, or trailer. Both the first circuit breaker 120 and the second circuit breaker 140 can be connected to a common bus 160, which in some embodiments 15 can be a large copper bar used to share power evenly to downstream equipment from upstream generators.

When the power source 110 is energized with both the first and second breakers 120, 140 closed, hydraulic fracturing equipment 170 can be supplied power while the PSS 20 130 stores excess electricity. The hydraulic fracturing equipment can be hydraulic fracturing pumps, blenders data vans, wireline equipment, boost pumps, cranes, lighting, chemical trailers, etc. Once load requirements increase for the equipment 170, the PSS 130 can release its stored power onto the common bus 160 in order to reduce the load on the power source 110. The power source 110 and the PSS 130 can share the burden of supplying power during stages of high power demand until the end of the fracturing stage. Before the next fracturing stage begins, the PSS 130 can replenish stored 25 electricity used previously until it is needed to discharge its power. This ability to recharge and discharge intermittently or continuously as needed ensures adequate power distribution to the system by the PSS 130 throughout an operation.

Also shown in FIG. 1A are third circuit breaker 180 and 30 fourth circuit breaker 190. Each of the third and fourth circuit breakers 180, 190 can be electrically connected to equipment 170. In the embodiment shown in FIG. 1A, each of the third and fourth circuit breakers 180, 190 are shown connected to pieces of equipment 170, such as, for example, 35 two hydraulic fracturing pumps. In practice, however, the present technology contemplates any appropriate ratio of circuit breakers to equipment, including connecting each circuit breaker to a single piece of equipment, or connecting each circuit breaker to more than two pieces of equipment.

40 One advantage to the present technology is that it is a more efficient way of providing power at peak times than known systems, such as simply providing another generator on site. In addition, the entire PSS package can be much smaller than a second generator, thereby taking up less space 45 on a pad. The storage system will also require significantly less rig up time due to having no fuel connections, crane lifts, or mechanical alignments.

FIG. 1B is a schematic depiction of the PSS 130 of the 50 embodiment of the hydraulic fracturing power system 100 of FIG. 1A. The PSS 130 can include a plurality of battery banks 131, each connected to a common PSS bus 132 via an optional battery bank circuit breaker 133. The common PSS bus 132 is also connected to a PSS circuit breaker 134 which is in turn electrically connected to circuit breaker 140 in the 55 switchgear housing 150.

Each of the connections in the PSS 130—between the battery banks 131 and battery bank circuit breakers 133, the battery bank circuit breakers 133 and the common PSS bus 132, the common PSS bus 132 and the PSS circuit breaker 134, and the PSS circuit breaker 134 and the second circuit breaker 140—are two way connections, as indicated by 60 double headed arrows. This means that electricity flows in

both directions between the various components. One advantage to this configuration is the ability of the battery banks 131 within the PSS 130 to constantly discharge and recharge as needed or allowed by the load demands of the system. Thus, when a heavy load is required, the PSS 130 can augment the power provided by power source 110 to help avoid overloading power source 110. Conversely, when a light load is required, the PSS 130 can pull excess power from power source 110 to recharge battery banks 131.

Referring now to FIG. 2A, there is shown an alternate hydraulic fracturing power system 200 according to an alternate embodiment of the present technology, including a power source 210 and a PSS 230. According to FIG. 2, the PSS 230 can be connected to the power source 210 in series before feeding power to a circuit breaker 215 in the switchgear housing 250. Upon reaching full capacity, the PSS 230 can disconnect internal batteries from the power source 210, thereby allowing it to bypass straight to the switchgear system.

In the configuration shown in FIG. 2A, the circuit breaker 215 will then act as a feeder breaker for two additional circuit breakers 280, 290. As shown, the circuit breaker 215 can be connected to circuit breakers 280, 290 via common bus 260. Circuit breaker 215 can be rated for higher amperage than circuit breakers 280, 290. Circuit breakers 280, 290 are in turn connected to hydraulic fracturing equipment 270. Each of the additional circuit breakers 280, 290 can be electrically connected to equipment 270. In the embodiment shown in FIG. 2A, each of the additional circuit breakers 280, 290 are shown connected to two pieces of equipment 270, such as, for example, two hydraulic fracturing pumps. In practice, however, the present technology contemplates any appropriate ratio of circuit breakers to equipment, including connecting each circuit breaker to a single piece of equipment, or connecting each circuit breaker to more than two pieces of equipment.

FIG. 2B is a schematic depiction of the PSS 230 of the embodiment of the hydraulic fracturing power system 200 of FIG. 2A. The PSS 230 can include a plurality of battery banks 231, each connected to a common PSS bus 232 via a battery bank circuit breaker 233. The common PSS bus 232 is also connected to an incoming PSS circuit breaker 235 and an outgoing PSS circuit breaker 236. Outgoing PSS circuit breaker 236 is in turn electrically connected to circuit breaker 215 in the switchgear housing 250.

Many of the connections in the PSS 230—between the battery banks 231 and battery bank circuit breakers 233, and the battery bank circuit breakers 233 and the common PSS bus 232—are two way connections, as indicated by double headed arrows. This means that electricity flows in both directions between the various components. One advantage to this configuration is the ability of the battery banks 131 within the PSS 130 to constantly discharge and recharge as needed. During a typical operation, power will discharge from the battery banks 231 to the circuit breaker 215 via the battery bank circuit breakers 233, the common PSS bus 232, and the outgoing PSS circuit breaker 236. Simultaneously, or as needed, power from the power source will recharge the battery banks 231 via the incoming PSS circuit breaker 235, the common bus 232, and the battery bank circuit breakers 233.

As shown in FIG. 3A, in certain embodiments of the technology, the hydraulic fracturing power system 300A can alternatively be powered by power transmission lines 305, with the power source 310 and the PSS 330 providing parallel power to the switchgear 350. In such an embodiment, the power source 310 and the PSS 330 can each be

attached to circuit breakers within the switchgear housing, which are in turn connected to the hydraulic fracturing equipment 370. This arrangement is similar to the embodiment shown in FIG. 1A, except that the power source 310 and the PSS 330 can be located at a remote location. The configuration of the circuit breakers within the switchgear housing 350 can be substantially similar to that of circuit breakers 120, 140, 180, 190 in the embodiment shown in FIG. 1A. In addition, the PSS 330 can have a similar structure to that described above and shown in FIG. 1B.

The arrangement shown in FIG. 3A, including the use of power transmission lines 305, could be beneficial if, for example, space at a well site is restricted, and power generation has to be stationed some distance from the pad. In such an embodiment, cables can be sized properly due to distance, and additional protection can be installed for safety reasons, such as three phase reclosers 325 (small circuit breakers placed at distribution poles to clear faults on cables that are running long distances). In the embodiment of FIG. 3, the PSS 330 can be connected to the transmission lines for remote operations, but may still draw power from the power source 310.

FIG. 3B shows an embodiment of the hydraulic fracturing power system 300B that shares characteristics of the embodiments of FIGS. 2A and 3A. That is, both the power source 310 and the PSS 330 are located at a remote location from the switchgear 350, and they are connected to the switchgear 350 in series. One advantage to this embodiment is that it requires only one set of transmission lines 305 between the power source 310/PSS 330 and the switchgear 350. In this embodiment, the configuration of the circuit breakers within the switchgear housing 350 can be substantially similar to that of circuit breakers 215, 280, 290 in the embodiment shown in FIG. 2A. In addition, the PSS 330 can have a similar structure to that described above and shown in FIG. 2B.

In yet another embodiment, shown in FIG. 4A, the hydraulic fracturing power system 400A can include similar features to the embodiment shown in FIG. 3A, including a power source 410 and a PSS 430. Moreover, the power source 410 is connected to the switchgear 450 via power transmission lines 405, and the power transmission lines can include safety features, such as reclosers 425. In the embodiment of FIG. 4A, the PSS 430 can also provide ancillary power. For example, if the power source 410 is a generator, and the generator shuts down during a fracturing stage, the PSS 430 can provide power to hydraulic fracturing equipment 470, including pumps, in order to flush the well so that chemicals and sand previously being pumped through the well can be completely removed from the well.

FIG. 4B shows an embodiment of the hydraulic fracturing power system 400B that shares characteristics of the embodiments of FIGS. 2A and 4A. That is, the power source 410 is located at a remote location switchgear 350, the PSS 430 is located at the well site, and the power source 410 and PSS 430 are connected to the switchgear 450 in series. One advantage to this embodiment is that the PSS 430 can provide power to the hydraulic fracturing equipment 470 even if the transmission lines 405 fail. Another advantage is that placing the PSS 430 at the wellsite allows for the provision of power at the wellsite without any local emissions or appreciative noise. In this embodiment, the configuration of the circuit breakers within the switchgear housing 450 can be substantially similar to that of circuit breakers 215, 280, 290 in the embodiment shown in FIG. 2A. In addition, the PSS 430 can have a similar structure to that described above and shown in FIG. 2B.

Another alternative embodiment of the present technology provides a hydraulic fracturing power system where the PSS can be used as black start for a power source that is a generator. Black starting is the process of supplying power to a generator that has been completely shut down to get it back up and running. Black start power can be used to power many different systems internal to a primary generator, including, for example, lighting, controls, blowers, cooling systems, lube pumps, oil pumps, starting motors, etc, until the generator is up and running and can provide its own power for these ancillary systems. Diesel generators can usually do this with battery power, but turbine generators require a larger power source, especially if gas compressors need to be operating before the engine can be fired. The configuration of the PSS relative to the switchgear and equipment in such a case can be similar to the embodiments shown in FIGS. 1-4. If enough power is stored in the batteries, the PSS system could support black starting operations without the need for a smaller standby generator to act as the black start power source. However, it could also utilize an external power source, such as solar panels, to recharge the storage system.

Use of the PSS in hydraulic fracturing power system of the present technology provides numerous advantages over known systems, including load leveling, frequency regulation, power quality control, emergency power, black start power, load bank capabilities, equipment reduction, reduced maintenance, and a simplified fuel supply. Each of these features is discussed in detail herein below.

First, with regard to load leveling, the PSS of the present technology has the ability to store electricity in times of low demand, and then to release that electricity in times of high power demand. As applied to electric powered hydraulic fracturing, stages that require relatively less load can provide a time for the PSS to charge up, or store electricity. In addition, the PSS can charge between stages or at the beginning of stages before full pump rate is achieved. Thereafter, power can be released in the stages of higher load requirements. This helps in increasing the lifespan of a power generating asset by decreasing its workload.

With regard to frequency regulation, the PSS can charge and discharge in response to an increase or decrease of microgrid frequency to maintain stored electricity within prescribed limits. This increases grid stability. In other words, the PSS can ramp up or down a generating asset in order to synchronize the generator with microgrid operation.

With regard to power quality control, the PSS can protect downstream loads such as sensitive electronic equipment and microprocessor based controls against short-duration disturbances in the microgrid that might affect their operation.

With regard to emergency power, in the event of a generator failure (due to, for example, a mechanical fault, electric fault, or due to a fuel supply loss), the PSS can provide sufficient electric power to flush the wellbore. This feature can prevent a "screen out" where the loss of fluid velocity causes the proppant in the hydraulic fracturing fluid or slurry to drop out and settle in the wellbore. Such a screen out can plug off the perforations and cause several days of downtime to clear. A screen out is a major concern in hydraulic fracturing and is considered a failure. The PSS can allow an electric hydraulic fracturing fleet to properly flush the well by being able to power the electric blender as well as sufficient hydraulic fracturing pumps to displace the proppant-laden slurry completely into the formation without generator power.

With regard to black start power, normally a small generator can be used to provide power to ancillary systems such as heaters, blowers, sensors, lighting, programmable logic controllers, electric over hydraulic systems, and electric over air systems for the larger generators. Such a generator can also be used to power the starters for these larger generators, which are often electric starters with a variable frequency drive or soft starter, or can be hydraulic starters with electric motors powering the hydraulic pumps.

If the PSS is properly charged, it can replace the black start generator to allow the larger generators (often turbines) to start from a black out condition.

With regard to load bank capabilities, the PSS can be used to test and verify generator performance during commissioning or after mobilization. It can also work for load rejections, to dissipate power during sudden shut downs, such as if the wellhead exceeds the maximum pressure and every frac pump needs to shut down simultaneously without warning.

With regard to equipment reduction, using an electricity storage system can allow electric fracturing operations to eliminate or reduce the use of a black start generator or supplemental generator, or a standby generator. Many times more than one large turbine generator is desired to provide power during peak demand during a hydraulic fracturing stage. Other times, a secondary generator can be held electrically isolated in standby in the event of a primary generator failure. Such secondary turbines can be replaced by the PSS, resulting in lower noise levels, less equipment on a pad, and faster mobilization times between well sites.

With regard to the reduced maintenance requirements, in some embodiments the PSS can be comprised of a solid state battery bank having very few moving parts. Thus, the PSS will require less maintenance than a generator utilizing a turbine or reciprocating engine.

With regard to the simplified fuel supply, in embodiments where the PSS is replacing a secondary or standby generator, the PSS will not require any fuel supply as it can be energized by a power grid. Therefore, any fuel connections for liquid or gas fuel can be removed from the system. This allows for a reduction in the number of connections and manifolds, as well as a reduction in the fuel volumes required during peak demand. In embodiments where the PSS replaces, for example, one of two turbines, all of the fuel equipment, hoses, and manifolding can be greatly reduced and simplified.

Although the technology herein has been described with reference to particular embodiments, it is to be understood that these embodiments are merely illustrative of the principles and applications of the present technology. It is therefore to be understood that numerous modifications may be made to the illustrative embodiments and that other arrangements may be devised without departing from the spirit and scope of the present technology as defined by the appended claims.

That claimed is:

1. A hydraulic fracturing power system, comprising:
a power source;
a power storage system;
an electric powered hydraulic fracturing pump configured to pressurize fluid in a wellbore to conduct hydraulic fracturing operations, and in selective electrical communication with the power source, the power storage system, or both; and
at least one circuit breaker between the power source, the power storage system, or both, and the electric powered hydraulic fracturing pump, the circuit

breaker having an open position that opens an electric circuit between the electric powered hydraulic fracturing pump and the power source, the power storage system, or both, and a closed position that closes the electric circuit, the at least one circuit breaker varying between the open position and the closed position as required to power the electric powered hydraulic fracturing pump and maintain a charge in the power storage system.

2. The hydraulic fracturing power system of claim 1, wherein the power storage system is at least one solid state battery selected from the group consisting of electrochemical capacitors, lithium ion batteries, nickel-cadmium batteries, and sodium sulfur batteries.

3. The hydraulic fracturing power system of claim 2, wherein the power storage system is at least one flow battery selected from the group consisting of redox batteries, iron-chromium batteries, vanadium redox batteries, and zinc-bromine batteries.

4. The hydraulic fracturing power system of claim 3, wherein the at least one battery is rechargeable.

5. The hydraulic fracturing power system of claim 1, wherein the at least one circuit breaker comprises a first circuit breaker and a second circuit breaker, the first circuit breaker electrically connected to the power source, and the second circuit breaker electrically connected to the power storage system.

6. The hydraulic fracturing power system of claim 5, wherein each of the first circuit breaker and the second circuit breaker is electrically connected to the electric powered hydraulic fracturing pump via a common bus.

7. The hydraulic fracturing power system of claim 1, wherein the at least one circuit breaker is a first circuit breaker, and wherein both the power source and the power storage system are electrically connected to the first circuit breaker.

8. The hydraulic fracturing power system of claim 1, wherein at least one of the power source and the power storage system are electrically connected to the at least one circuit breaker via a power line.

9. The hydraulic fracturing power system of claim 1, wherein the power storage system is mounted to a trailer.

10. The hydraulic fracturing power system of claim 1, wherein the at least one circuit breaker is substantially enclosed in a switchgear housing.

11. A system for powering an electric hydraulic fracturing pump, comprising:

a power storage system having;

an electric powered hydraulic fracturing pump configured to pressurize fluid in a wellbore to conduct hydraulic fracturing operations, and in selective electrical communication with the power storage system; and

at least one circuit breaker between the power storage system and the electric powered hydraulic fracturing

pump, the circuit breaker configured to facilitate or prevent electrical communication between the power storage system and the electric powered hydraulic fracturing pump and;

a power source wherein both the power source and the power storage system are electrically connected to the at least one circuit breaker, and the at least one circuit breaker facilitates or prevents communication between the power storage system, the power source, and the electric powered hydraulic fracturing pump as required to power the electric powered hydraulic fracturing pump and maintain a charge in the power storage system.

12. The system for powering the electric hydraulic fracturing pump of claim 11, wherein the power storage system is at least one solid state battery selected from the group consisting of electrochemical capacitors, lithium ion batteries, nickel-cadmium batteries, and sodium sulfur batteries.

13. The system for powering the electric hydraulic fracturing pump of claim 12, wherein the power storage system is at least one flow battery selected from the group consisting of redox batteries, iron-chromium batteries, vanadium redox batteries, and zinc-bromine batteries.

14. The system for powering the electric hydraulic fracturing pump of claim 11 wherein the at least one circuit breaker comprises a first circuit breaker and a second circuit breaker, the first circuit breaker electrically connected to the power source, and the second circuit breaker electrically connected to the power storage system.

15. The system for powering the electric hydraulic fracturing pump of claim 11 wherein at least one of the power source and the power storage system are electrically connected to the at least one circuit breaker via a power line.

16. The system for powering the electric hydraulic fracturing pump of claim 11, wherein the at least one circuit breaker is substantially enclosed in a switchgear housing.

17. The system for powering the electric hydraulic fracturing pump of claim 11, wherein the power storage system is rechargeable.

18. The system for powering the electric hydraulic fracturing pump of claim 16 wherein the power source is electrically connected to the at least one circuit breaker via a power line, and where the power storage system is located adjacent the switchgear housing and electrically coupled directly to the switchgear housing without a power line.

19. The system for powering the electric hydraulic fracturing pump of claim 16, further comprising:

software in communication with the power storage system, the software configured to monitor the state of the power storage system and to integrate control of the power storage system with other features of the system for powering electric hydraulic fracturing equipment.
